United States Patent Office

Des. 187,588
Patented Apr. 5, 1960

187,588

KNIFE

Walter Daemmer, Solingen-Merscheid, Germany, assignor to C. Friedr. Ern, Solingen-Wald, Germany

Application August 21, 1958, Serial No. 52,329

Claims priority, application Germany June 11, 1958

Term of patent 14 years

(Cl. D22—3)

FIG. 1

FIG. 2

FIG. 5

FIG. 3

Fig. 1 is a top plan view of a knife showing my new design;

Fig. 2 is a side elevational view thereof;

Fig. 3 is an end elevational view looking toward the butt end of the handle shown in Fig. 1;

Fig. 4 is an end elevational view looking toward the blade end of the handle of Fig. 1; and

Fig. 5 is a bottom plan view thereof.

The dominant features of my design reside in the portions shown in full lines.

I claim:

The ornamental design for a knife, as shown and described.
